UNITED STATES PATENT OFFICE.

GRANT E. MENDELL, OF CHICAGO, ILLINOIS.

RULING DEVICE.

1,297,217.

Specification of Letters Patent. Patented Mar. 11, 1919.

Application filed March 16, 1918. Serial No. 222,890.

To all whom it may concern:

Be it known that I, GRANT E. MENDELL, a citizen of the United States, residing at Chicago, in the county of Cook and State of Illinois, have invented certain useful Improvements in Ruling Devices, of which the following is a specification, reference being had therein to the accompanying drawing.

The present invention has reference generally to improvements in that class of inventions known as stationery, and more particularly relates to a ruling device.

As the primary aim and object this invention contemplates the provision of novel disk ruling or marking pens as well as means for rotatably supporting the pens.

It is an additional and equally important object of this invention to provide novel inking pad supports for removable engagement with the main handle in proximity to the disk pens so that the pens will be automatically supplied with ink when the device is in use.

It is a more specific object of this invention to provide improved guides on the holder for coöperation with a ruler when the device is in use; and to provide improved means for removably retaining the pad supports and consequently the pads in position.

Among the other aims and objects of this invention may be recited the provision of a device of the character mentioned with a view to compactness, and in which the number of parts are few, the construction simple, the cost of production low, and the efficiency high.

Other improvements and novel details in the construction and arrangement of the various parts will be brought out more in detail in the description to follow, which for a clear understanding of the invention should be considered in connection with the accompanying drawings, forming a part hereof, and wherein is disclosed for the purpose of illustration a convenient and satisfactory embodiment of the invention. It is to be noted in this connection that minor changes in the construction and arrangement of parts may be made without departing from the spirit of the invention or the principle of operation of the various parts.

The invention is clearly illustrated in the accompanying drawings, in which—

55 Figure 1 is a side elevation thereof;
Fig. 2 is a top plan;

Fig. 3 is an enlarged section taken on line 3—3 of Fig. 1 in the direction in which the arrows point; and

Fig. 4 is a perspective detail of one of the 60 pad supports.

Similar characters of reference are employed in all of the above described views, to indicate corresponding parts.

Referring now, more particularly, to the 65 accompanying drawings, there is provided a holder or handle 1 the respective ends of which are bifurcated to provide sockets 2 and spaced resilient arms 3. One of each pair of the arms is provided on one marginal edge with an inwardly extending arcuate slot 4 and is further provided with a guide 5 which extends longitudinally from the outer end of the arm and in alinement with the opposite marginal edge thereof as 70 indicated in Fig. 1 for a purpose that will presently appear.

As intimated, improved ruling or marking means have been provided in the present instance consisting of double disk pens 6 and 80

the single disk pen 7. The double disk pen consists of a pair of spaced disks 8 arranged in rigid relation with respect to each other, the outer edges thereof being beveled toward the inner surfaces as indicated by the numeral 9. Supporting trunnions or axles 10 extend from the outer faces of the disks and centrally thereof having washers 11 arranged thereabout preparatory to being journaled in opposed openings 13 in one 90 pair of arms. The disk pen 7 has its outer edge beveled on opposite sides as indicated by the numeral 14 while trunnions or axles 15 extend from the opposite faces and centrally thereof. Washers 16 are mounted 95 about the trunnions in opposed openings 17 in the other pair of arms.

With a view toward providing improved means for inking the disks as the device is being used the pads 18 are employed. The 100 pads are arranged between the side walls 19 of pad supports 20 which are insertible in the sockets 2. Opposed flanges 21 extend inwardly from the outer edges of the opposite sides 19 and serve to facilitate the retention of the pads in the supports. The bottom of each support is flattened as at 22 substantially intermediate the ends so that the supports will be effectively seated in the sockets. Suitable means for retaining 105 the pads and also the supports in position consist of a screw 23 one end of which is

anchored as at 24 to one of the sides 20 while the opposite end projects through the opposite side and is engageable in the adjacent arcuate slot 4. The screws are engaged 3 by knurled nuts 25 which cooperate with the outer face of the adjacent arm in clamping the parts in position, the arrangement being illustrated in Fig. 3.

In use, assuming that the parts have been 10 assembled in the manner described the handle is engaged in a manner similar to the manner in which an ordinary drawing pen is engaged while both of the guides 5 are adapted to alternately cooperate with the 15 ruler (not shown) in guiding the movement of the device. Of course the pad supports will be readily removed by loosening the desired knurled nut. This is done when it is desired to place either another support 20 and pad or a pad which is saturated with a different colored ink.

It is to be understood from the foregoing description that any number of disk pens may be arranged integral and in spaced relation to the other and by varying the size of the device the usual lines on a music sheet 30 may be effectively drawn.

As many changes could be made in the above construction and many apparently 20 widely different embodiments of this invention could be made without departing from the scope thereof, and it is intended that all

matter contained in the above description or shown in the accompanying drawings shall be interpreted as illustrative and not in a 35 limited sense. It is also to be understood that the language used in the following claim is intended to cover all the generic and specific features of the invention herein described and all statements of the scope of 40 the invention, which as a matter of language might be said to fall therebetween.

Having thus fully described this invention, what is claimed as new and desired to be secured by Letters-Patent, is:—

A device of the character described including a holder, spaced arms provided on one end thereof, a rotatably mounted marking element between the arms, a guide projecting from one of the arms, an arcuate pad support seated between the arms, a pad mounted in the support and arranged in proximity to the outer edge of the marking element for applying ink thereto, a screw carried by one side of the support and extending through the opposite side and removably engaged in the adjacent arm, and an adjustable element for engagement with the outer end of the screw for cooperating 50 with the adjacent arm in retaining the pad and the support in position.

In testimony whereof I affix my signature.

GRANT E. MENDELL.
